United States Patent Office.

GARRETTSON SMITH AND HENRY BROWN, OF PHILADELPHIA, PENNSYLVANIA, ASSIGNORS TO LEIBRANDT & McDOWELL, OF SAME PLACE.

Design No. 2,574, dated February 12, 1867.

DESIGN FOR A COOK'S STOVE.

The Schedule referred to in these Letters Patent and making part of the same.

TO ALL WHOM IT MAY CONCERN:

Be it known that we, GARRETTSON SMITH and HENRY BROWN, carvers, of the city of Philadelphia, in the State of Pennsylvania, have invented or produced a new and original Design for a Cook's Stove; and we do hereby declare that the following is a full, clear, and exact description of the same, reference being had to the accompanying drawing, making a part of this specification, and to the letters of reference marked thereon.

In the said drawing, the stove is represented in perspective, showing the front and one side, and also the top; the opposite "side" of the stove corresponding in each particular with the side shown in the drawing. The doors *a b c*, of the sides, have each a raised oval centre, on a raised panel ornamented with raised figures, and surrounded by an edge-moulding, as shown in the drawing. The doors *d e*, of the front, are ornamented raised panels, surrounded by edge-mouldings, and provided with oval centres of the same patterns as those of the "sides." The top and the bottom plates are each provided with an edge-moulding, as shown. We designate the stove as "The Farmer."

We claim the design for a cook's stove, termed "The Farmer," as shown and described.

GARRETTSON SMITH,
HENRY BROWN.
